UNITED STATES PATENT OFFICE.

CLINTON L. BOPP, OF WATERLOO, IOWA.

ELECTRICAL SIGNALING DEVICE.

1,073,024.

Specification of Letters Patent.

Patented Sept. 9, 1913.

Application filed September 8, 1911. Serial No. 643,269.

To all whom it may concern:

Be it known that I, CLINTON L. BOPP, a citizen of the United States, residing at Waterloo, in the county of Blackhawk and State of Iowa, have invented certain new and useful Improvements in Electrical Signaling Devices; and I do hereby declare the following to be a full, clear, and exact description of the invention, such as will enable others skilled in the art to which it appertains to make and use the same.

This invention relates to mechanism for holding switches closed which are moved to their closed position by the deflection of a rail and has as an object to provide means operable by the rail for closing and holding closed a contact.

A further object of the invention is to provide an improved form of third rail for carrying the current to produce electric signals.

A further object of the invention is to provide improved means for closing the circuit and retaining the circuit in such closed position until the train has passed from the contact.

With these and other objects in view the invention comprises certain novel constructions, combinations and arrangements of parts as will be hereinafter more fully described and claimed:

The drawing is a view, largely diagrammatic, of the improved invention.

This invention may be used in the disclosure shown in my copending application 671,369, filed Jan. 16th, 1912, but in the following specification it is described as a complete switch closing device and is independent of any particular signaling system.

As indicated in the drawing, one rail 1 is shown with one wheel 2 of a conventional engine or car, the cab or car body of which is shown at 3 with the axle at 4.

Adjacent the rail 1 a column 5 is erected carrying a housing 6 on the upper end, such housing and column being rigidly secured and stationary adjacent such rail. Between the column 5 and the rail 1 a fulcrum block 7 is erected upon which is ful-

crumed a lever 8 having a bifurcated end as at 9 to embrace the lower flange of the rail 1 so that when the rail 1 is deflected by the passage of an engine or a train thereover, the shorter end of the lever 8 will be depressed to raise the longer end which extends into the column 5.

Within the column 5 a rod 10 is mounted to reciprocate vertically, connected with the longer end of the lever 8 as by the link 11 and carrying a spring 12 at its upper end which engages the lower end of a plunger 13 also mounted to reciprocate vertically within the column 5 and extending upwardly into the housing 6. The plunger 13 is provided with an insulating section 14 and spring contacts 15 and 16 are secured within the housing 6 and in normal engagement with the insulating section 14.

At its upper end the plunger 13 carries an armature 17 positioned and proportioned to engage the cores 18 of the electro magnets 19 which are rigidly secured within the housing 6.

Current over the line wire 20 from the source of energy 21 passes through the wire 22 in the column 5 and to the contact 16. When the rail 1 is deflected to raise the longer end of the lever 8 the rod 10 and plunger 13 are also raised so that the contacts 15 and 16 engage the metallic or conductor portion of such plunger so that the current delivered to the contact 16 passes through such plunger to the contact 15, thence by the wire 23 to the magnets 19 which are energized, magnetizing the cores 18. The lifting of the plunger 13 has brought the armature 17 adjacent to or in contact with the cores 18 so that when they have become magnetized they serve to hold such armature in engagement with the cores and to permit the current to continue to flow through the conductor portion of the plunger 13, such movement being permitted by the spring 12 which compensates for any unevenness of action or oscillation due to the continued passing of cars or engines over the track section controlling the lever 8.

After passing through the magnets the

current passes through the wire 24 to the plate 25 of the third rail which is preferably constructed of angle or other structural material 26 with an over-turned housing 27 to protect the plate 25 from the weather. The rail is also provided with an angularly disposed guide strip 28. The engine or car which is designed to receive the signal is provided with a bracket 29 which carries a spring-pressed lever 30 terminating in a brush 31 positioned to engage the plate 25 of the third rail and preferably, though not necessarily, with a limiting screw 32. The current delivered by the wire 24 to the plate 25 is therefore gathered by the brush 31 and passing through the lever 30 and bracket 29 is carried by the wire 33 to the signaling device shown conventionally as a bell 34. From the signaling device 34 a wire 35 returns the current to the axle 4 of the car where it passes through the rail 1 and wire 36 to ground, completing the circuit. Preferably, though not essentially, a switch 37 is placed in the cab or car for controlling the current.

The present device is designed to prevent the unauthorized actuation of signals for by its use it will be impossible to move the lever 8 by any means other than passing a train or engine over the track as no other available means will cause a deflection of the rail and as the other members are secured from being tampered with and as the lever 8 is so connected with the rail that it cannot be moved without the movement of the rail the whole device is secure from unauthorized interference. The line wire 20, desired to carry any desired signal, is therefore open until the circuit is closed by the deflection of the rail 1 and the contacting of the spring contacts 15 and 16 with the conductor portion of the plunger 13. As soon as this takes place the circuit through the cab or car is completed and any signals can be communicated directed thereto from such line wire. In use the magnets will continue to hold the circuit closed until the train passes from contact with the third rail 25 which may be of any length desired.

50 I claim:—

1. In a signaling device, a housing, an electric circuit leading into the housing, a plunger mounted to reciprocate within the housing and provided with an insulating section, contacts engaging upon opposite sides of the insulating section and in connection with the circuit, a rail located adjacent the housing, a lever extending from the rail into the housing and adapted to raise the plunger with the deflection of the rail to bring the contacts into engagement with the conductor portion of such plunger, and means to hold the plunger in raised position until the circuit is broken.

2. In a signaling device, a housing, a 65 plunger mounted to reciprocate vertically within the housing and provided with insulating and conducting sections, contacts bearing against the opposite sides of the plunger and normally engaging the insulating section, an electromagnet positioned and energized to hold the plunger in raised position, a rail adjacent the housing, a lever extending from the rail and adapted to raise the plunger when the rail is deflected, and an electric circuit including the contacts and the electromagnet closed by the engagement of the contacts with the conductor section of the plunger.

3. In a signaling device, a housing, an 80 electric circuit leading into the housing, a switch located within the housing, a rail disposed adjacent to the housing, a lever connected with and actuated by the rail, and flexibly connected with the switch, said 85 switch being closed by the lever as the rail deflects, and a third rail adjacent to the rail connected with the switch in the housing.

4. In a signaling device, a housing, an 90 electric circuit leading into the housing, a switch located within the housing, a rail disposed adjacent to the housing, a lever connected with and actuated by the rail and flexibly connected with the switch, said 95 switch being closed by the lever as the rail is depressed means for holding the switch in its closed position as the rail rises, and a third rail adjacent to the rail connected with the switch in the housing.

5. In a signal device a housing, an electric circuit leading into the housing, a lever entering said housing, a two part plunger connected to said lever, a contact carried by one part of said plunger, a rail engaging said lever and adapted to raise said plunger 105 as the rail deflects, means carried by said housing for closing the circuit through said contact as the plunger rises, a third rail adjacent said housing, and electro-magnetic means associated with said third rail, said 110 contact, and said electric circuit for retaining the contact closed as the other part of said plunger descends.

6. In a signaling device, a housing, an 115 electric circuit entering the housing, a switch disposed within the housing, a rail located adjacent the housing, a lever engaging the rail and adapted to be moved by the deflection of the rail to close the switch, a 120 third rail adjacent the rail in electrical contact with the circuit entering the housing, a signaling apparatus moving upon the rail, and means carried by the signaling apparatus for engaging the third rail at the time the rail is deflected.

7. In a signaling device, a housing, an 125 electric circuit entering the housing, a switch disposed within the housing, a rail disposed

adjacent the housing, a lever engaging the rail and adapted to be moved by the deflection of the rail to close the switch, a third rail located adjacent the rail and electrically connected with the circuit entering the housing, a vehicle moving upon the rail and carrying a signaling device and a brush carried by the vehicle adapted to engage the

third rail at the time the rail is deflected to close the switch.

In testimony whereof I affix my signature in presence of two witnesses.
